UNITED STATES PATENT OFFICE.

MOSES ROSENTHAL, OF CHICAGO, ILLINOIS.

DESIGN FOR A RUG.

48,500.

Specification for Design.

Patented Feb. 1, 1916.

Application filed November 8, 1915. Serial No. 60,442. Term of patent 3½ years.

To all whom it may concern:

Be it known that I, MOSES ROSENTHAL, a citizen of the United States of America, residing at Chicago, in the county of Cook and State of Illinois, have invented a new, original, and ornamental Design for Rugs, of which the following is a specification, reference being had to the accompanying drawing, forming a part thereof.

The figure is a plan view of a portion of a rug illustrating my new design.

I claim:

The ornamental design for a rug, as shown.

MOSES ROSENTHAL.
